UNITED STATES PATENT OFFICE.

JOHN EDWARD OGDEN, OF MOUNTAINVILLE, CORNWALL, NEW YORK.

REINFORCED-THREAD EXPANSION SHIELD.

Application filed January 11, 1921. Serial No. 436,492.

To all whom it may concern:

Be it known that I, JOHN EDWARD OGDEN, a citizen of the United States of America, and a resident of Mountainville, town of 5 Cornwall, Orange County, and State of New York, have invented certain new and useful Improvements in Reenforced-Thread Expansion Shields, of which the following is a specification.

10 This invention relates to expansion shields which are used in combination with lag screws to effect a better securement of the lag screws in various kinds of material. Expansion shields of this character are usually provided with a tapered bore, the shield itself being in the form of a cylinder. It will therefore be seen that the thickness or depths of the walls of the shield varies with the configuration or taper of the bore. It is 15 an object of my invention to improve devices of this character by so arranging the walls of the shield that great resistance shall be offered to the wedging and subsequently deforming action of the lag screws as the 20 latter are screwed home into the shield to firmly secure the shield within the hole in which it is placed. This and other objects of the invention are accomplished by forming the shield in accordance with the forms 25 illustrated in the accompanying drawings forming part of this specification and particularly described herein.

Referring now to the drawings, Fig. 1 is an elevation of a helically corrugated expansion shield which embodies one form of the invention, there being longitudinal indentations impressed across the threads on each side of the divisional line of the shield and from the outside thereof.

40 Fig. 2 is a plan view of the shield shown in Fig. 1;

Fig. 3 is a bottom plan view thereof, and

Fig. 4 is a sectional elevation thereof on the line 4—4 of Figure 3.

45 Fig. 5 is an elevation of a modified form of shield in which the longitudinal indentations in the threads are impressed therein from the inside or bore of the shield.

Fig. 6 is a bottom plan view of the shield 50 shown in Fig. 5; and

Fig. 7 is a sectional elevation thereof taken on line 7—7 of Fig. 6.

Figs. 8 and 9 are views similar to Figs. 3 and 6 respectively, showing the division

plane or line of the shields as at the right 55 angles to that shown in those figures.

Fig. 10 is an elevation of a modified form of the invention in which part of the exterior wall of the shield comprises triangular sections of sheet metal extending from the bottom of the shield upwardly, the sections being bent back from the divisional edges thereof and longitudinally indented.

Fig. 11 is a plan view of the shield shown in Fig. 10;

Fig. 12 is a bottom plan view thereof, the bore being shown as of "hour glass" form; and

Fig. 13 is an elevation of one of the sections making up the shield, the view being 70 taken on the line 13—13 of Fig. 12.

Fig. 14 is a view similar to Fig. 12 but showing a modified form of bore.

Fig. 15 is an elevation of another modified form of shield, showing exterior fingers extending from the edges of the segments and having their tips folded back and down into the bottoms of the helical corrugations.

Fig. 16 is a bottom plan view of the shield shown in Fig. 15.

Fig. 17 is a view similar to Fig. 16, but showing the tips of the fingers as extended and bent back under the fingers.

Fig. 18 is a view similar to Fig. 16, but showing the finger tips of Fig. 17 as 85 crimped.

Fig. 19 is an elevation of a modified form of shield in which the fingers of Fig. 15 are bent to lie within the bore of the shield instead of on the outside thereof as in Fig. 90 15.

Fig. 20 is a bottom view of the shield shown in Fig. 19.

Fig. 21 is an elevation of a modified form of shield in which is combined the triangular sections of Fig. 10 and the fingers of 95 Fig. 15.

Fig. 22 is a bottom plan view of the shield shown in Fig. 21.

Fig. 23 is a view similar to Fig. 22, but 100 showing the tips of the fingers as extended and folded under the fingers.

Fig. 24 is an elevation of a modified form of shield in which part of the exterior wall of the shield comprises triangular sections of sheet metal extending from the bottom of the shield upwardly, the sections being bent back from the bottom of the shield in-

stead of from the divisional edges thereof as in Fig. 10 and transversely indented.

Fig. 25 is a bottom plan of the shield shown in Fig. 24;

5 Fig. 26 is an elevation of one of the sections making up the shield shown in Fig. 24, the view being taken on the line 26—26 of Fig. 25, and

10 Fig. 27 is a transverse section taken on the line 27—27 of Fig. 26.

Fig. 28 is an elevation of a shield which differs from that in Fig. 24 by having its triangular sections bent backward from its divisional edges instead of from the bottom 15 of the shield as in Fig. 24.

Fig. 29 is a bottom plan view of the shield shown in Fig. 28.

Fig. 30 is an elevation of a shield which differs from that in Fig. 21 by having trans- 20 verse instead of longitudinal indentations.

Fig. 31 is a bottom plan view of the shield shown in Fig. 30.

Fig. 32 is a view similar to Fig. 31 but showing the finger tips as extended and folded under.

Like characters of reference designate corresponding parts through the drawings.

40 designates a tubular shield of stamped or pressed metal of substantially uni- 30 form thickness, either divided longitudinally throughout the greater part of its length along lines which are preferably in the same plane, or else divided throughout its entire length whereby independent cylindrical seg- 35 ments are formed, the segments being main- tained in axial alinement by any suitable means as by a spring wire 41 seated in a groove 41' in the segments. The exterior of the shield is a cylinder while the bore is 40 tapered from the outer to the inner end thereof. The bore in cross section is preferably not circular but has constricted portions preferably at diametrically opposite points. The bore is provided with threads 45 42 of a pitch to receive a lag screw. These threads are helical corrugations which vary in depth sufficiently to make the exterior wall of the shield cylindrical.

The shield preferably comprises two sym- 50 metrical segments, the plane of division between the segments being indicated through- out the several views by the line *a—b*. While I prefer to make the bore of the shield of substantially elliptical form and to di- 55 vide the shield along the major axis of the ellipse I may as indicated in the drawings, divide it along the minor axis thereof and make the bore of hour glass form without departing from the spirit of the invention. 60 Furthermore it will be understood that while I have shown the shield as divided into two symmetrical segments, it may be composed of a further plurality of symmetrical segments without departing from the spirit of 65 the invention.

Referring now more specifically to Figures 1 to 9 of the drawings it will be seen that the shield is provided with helical corrugations 42 which begin a short distance from the top or outer end of the shield and 70 extend throughout the length thereof. In view of the fact that the bore of the shield gradually decreases in cross sectional area from the outer to the inner end thereof the corrugations likewise vary in depth, being 75 of maximum depth at the bottom or inner end of the same. When the bore has a major and a minor axis, the wall of the shield will thus be of minimum depth or thickness on the major axis of the bore as indicated at 80 43 and of maximum depth on the minor axis thereof as indicated at 44. The deeper parts of the shield walls are provided with longitudinally extending indentations 45. These indentations lie across the threads or 85 corrugations and gradually increase in width and depth from the outer to the inner end of the shield. In Figs. 1 to 4 and Fig. 8 these indentations are shown as im- 90 pressed from the outside toward the bore of the shield while in Figs. 5 to 7 and Fig. 9 they are shown as impressed in the screw threads within the bore of the shield. When the indentations are impressed from the out- 95 side toward the bore of the shield the depth of the same is such that they will not interfere with the free passage of threads of the lag screw, or in other words the indentations are not deep enough to form obstructions 100 against the entry of the lag screw which, as has been pointed out, is threaded into the bore of the shield to expand the same. When the indentations are impressed into the corrugations from the inside of the shield they are preferably no deeper than the depth of the lag screw threads. The upper noncorrugated part of the shield is preferably provided with outwardly extending indentations, 46 which serve to prevent 105 rotation of the shield when the lag screw is 110 initially turned in the bore of the shield.

In Figs. 8 and 9 I have shown that the plane of division of the shield may be on the major instead of on the minor axis of the bore thereof without departing from the 115 spirit of the invention.

In Figs. 10 to 14 I have shown a modified form of the invention. The bore of the shield, as in the previously described forms of the invention, is helically corrugated to 120 form screw threads to receive a lag screw. The cylindrical form of the shield, however, is obtained not by increasing the depth of the corrugations at either side of the minor axis of the bore but by folding over from 125 the longitudinal edges of the segments of the shield, triangular sections 47 of the sheet metal. Into these sections are impressed longitudinally extending indentations 45', prefer- 130 ably a plurality thereof as shown, Fig. 130

12 also shows the bore as of hour glass form and in an illustration of one of the forms the bore may have in all of the modifications of the inventions without departing from the spirit of the invention.

In Figs. 15 to 18 I have shown another form of my invention in which fingers or finger-like projections 48 go to make up part of the cylindrical wall of the shield. 10 These fingers extend radially from the bottom of the exterior corrugations until the cylindrical diameter of the shield is reached and are then bent over until their tips rest in the bottom of the corrugations as clearly 15 illustrated in Fig. 16. In Fig. 17 I have shown the fingers 48 as provided with extended tips 50 which are bent back and under the fingers and lie in the bottoms of the corrugations. In Fig. 18 I have shown 20 the tips 50 as made somewhat longer and crimped.

Referring now to Figs. 19 and 20 it will be seen that I have shown the fingers 48 as being bent inwardly and forming part of the 25 thread in the bore. The exterior cylindrical form of the shield is thus had, as in the form shown in Figs. 1 to 9, solely by the depth of the helical corrugations 42.

In Figs. 21 to 23 I have shown a further 30 development of my invention. The longitudinally indented triangular sections 47 (Figs. 10 to 14) are provided with fingers 48' which extend from the hypotenuse side of the triangular sections 47 and have their 35 tips resting in the bottom of the corrugations. In Fig. 23 I have shown the tips as somewhat longer and bent back and under the finger similar to the arrangement shown in Fig. 17.

40 In Figs. 24 to 27 I have shown the triangular sections 47 as being bent up from the bottom or inner end of the shield instead of from the divisional edges thereof. As a further modification of my invention I have 45 shown these triangular sections as indented transversely instead of longitudinally. These indentations are in the form of helical corrugations 49 corresponding in pitch to the threads 42 of the bore. As shown they 50 gradually increase in depth from the outer to the inner end of the shield being at a maximum at the bottom or inner end thereof. It will be understood that the exterior 55 of the shield is cylindrical as in the other modifications. The roots 51 of these helical indentations rest in the depressions 52 formed in the underlying shield wall by the screw threads 42 of the bore.

60 In order to make clear that the transverse indentations 49 may be incorporated into triangular sections 47 which are bent over from the divisional edges of the shield, I have shown such construction in Figs. 28 and 29. It will of course be understood that 65 the divisional edges in this construction will

not appear as a cell-like arrangement but will appear as a closed triangular wall between the bore and exterior cylindrical surface of the shield as clearly shown in Fig. 13.

Figs. 30 and 31 show the transversely indented triangular sections as provided with laterally extended fingers 48'. The tips of these fingers rest in the bottoms of the depressions 52 formed by the threads 42. Fig. 32 shows the fingers as having tips 50 bent back and under the triangular sections and lying in the bottom of the depression 52 of the thread 42.

In all of the forms of expansion shield which have been shown, the construction is 70 such that there is an excess of metal on the bottom or inner end of the shield, this excess of material gradually decreasing toward the outer end of the shield. In all of the constructions the configuration of the bore is 75 80 such that it has a plurality of axes of different length. Inasmuch as the exterior of the shield is cylindrical in form it follows that the thickness of the shield from the inside to the outside thereof will be different at different parts of the same, being of less thickness on the axis of greatest length and of least thickness on the axis of shortest length.

In order to prevent undesirable collapse 90 of the walls of the shield, indentations have 95 been provided for the purpose of stiffening the corrugations. These indentations are preferably arranged in pairs on either side of the minor axis of the bore either on the outside of the shield or on the inside thereof as shown in Figs. 1 to 9. This construction makes possible a firm securement of the shield in its hole since the walls at their 100 points of greatest depth will not collapse 105 prematurely or in other words will only gradually be deformed as the lag screw is screwed into the bore. In those forms of the invention wherein the cylindrical form of the shield comprises in part triangular sections a construction is obtained which also 110 insures that the walls at their points of greatest depth will stand up under the wedging action of the lag screw and only be gradually deformed thereby as the same is screwed home. The provision of longitudinal indentations in the triangular sections is 115 advantageous not only because it serves to very materially stiffen the sheet metal but also because the tendency for the shield to rotate about its axis is obviated. The transverse corrugations in said sections serve primarily to stiffen the material. In those forms wherein the triangular sections are provided with laterally extended fingers the latter serve to give an increase of metal in 120 the shield and also to add to the rigidity of the same. The same result follows when fingers are bent over from the divisional edges of the shield as shown in Figs. 15 to 20.

125

130

While I have shown and described my invention as capable of embodiment in a number of forms, it will be understood that the showing is merely illustrative of the invention and is not to be taken as a limitation thereof. Reference is to be had to the appended claims for the scope of the invention.

What I claim is:

1. A tubular expansion shield having walls of substantially uniform thickness which are helically corrugated to form a threaded bore, said bore being gradually constricted in at least one plane which includes the axis of the shield, and reinforcing open bends in the metal near the plane of said constriction.
2. A tubular expansion shield, having walls of substantially uniform thickness which are helically corrugated to form a threaded bore, said bore being gradually constricted in at least one plane which includes the axis of the tube, and reinforcing corrugations in the metal near the plane of said constriction.
3. A tubular expansion shield having walls of substantially uniform thickness which are helically corrugated to form a threaded bore, the outer parts of the shield lying in a cylindrical surface, said bore being gradually constricted in at least one plane which includes the axis of the tube, and reinforcing corrugations in the metal near the said plane or planes where the distance between the outer parts of the shield and the bore is greatest.
4. A tubular expansion shield having walls of substantially uniform thickness, said shield being longitudinally divided throughout at least a part of its length and helically corrugated to form a threaded bore, the outer parts of the shield lying in a cylindrical surface, said bore being gradually constricted in at least one plane which includes the axis of the tube, and reinforcing corrugations in the metal near the said plane or planes where the distance between the outer parts of the shield and the bore is greatest.
5. A tubular expansion shield having walls of substantially uniform thickness with the outer parts thereof lying in a cylindrical surface, said shield being longitudinally divided throughout at least a part of its length and helically corrugated to form a threaded bore with the threads thereof gradually increasing in depth from the outer to the inner end of the shield in at least one plane which includes the axis of the tube and to a greater extent than in planes removed therefrom, and reinforcing open bends in the metal near the said plane or planes of maximum increase in depth of the threads.
6. An expansion shield comprising a plurality of cylindrical sections which together

form a tubular device, the walls of each section being of substantially uniform thickness and helically corrugated to form parts of a threaded bore, said corrugations gradually increasing in depth from the outer to the inner end of the section and to a greater degree at the edges of the section than at lines intermediate the edges and each section having reinforcing open bends near said edges.

7. A tubular expansion shield of sheet metal helically corrugated to form a threaded bore, said bore being gradually constricted in at least one plane which includes the axis of the shield, and reinforcing open bends in the metal near the plane of said constriction.

8. A tubular expansion shield of sheet metal helically corrugated to form a threaded bore, the outer parts of the shield lying in a cylindrical surface, said bore being gradually constricted in at least one plane which includes the axis of the tube, and reinforcing corrugations in the metal near the said plane or planes where the distance between the outer parts of the shield and the bore is greatest.

9. A tubular expansion shield of sheet metal with the outer parts thereof lying in a cylindrical surface, said shield being longitudinally divided throughout at least a part of its length and helically corrugated to form a threaded bore with the threads thereof gradually increasing in depth from the outer to the inner end of the shield in at least one plane which includes the axis of the tube and to a greater extent than in planes removed therefrom, and reinforcing open bends in the metal near the said plane or planes of maximum increase in depth of the threads.

10. An expansion shield comprising a plurality of similar sections of sheet metal together forming a tubular device, each section being helically corrugated to form parts of a threaded bore, said corrugations gradually increasing in depth from the outer to the inner end of the section and to a greater degree at the edges thereof than on lines intermediate the edges, and each section having reinforcing open bends near said edges.

11. An expansion shield of sheet metal in the form of a cylinder having a bore of gradually decreasing cross sectional area, helical corrugations of constant pitch but increasing depth in the walls of the shield, and reinforcing indentations extending transversely across the corrugations.

12. An expansion shield of sheet metal in the form of a cylinder having a bore of gradually decreasing cross sectional area, helical corrugations of constant pitch but increasing depth in the walls of the shield, and reinforcing indentations in the corrugations extending longitudinally of the shield.

13. An expansion shield of sheet metal in the form of a cylinder having a bore of gradually decreasing cross sectional area, helical corrugations of constant pitch but increasing depth in the walls of the shield, and reinforcing indentations in the corrugations extending longitudinally of the shield, said indentations gradually increasing in depth. 55
14. An expansion shield of sheet metal in the form of a cylinder having a bore of gradually decreasing cross sectional area, helical corrugations of constant pitch but increasing depth in the walls of the shield, and reinforcing indentations in the corrugations extending longitudinally of the shield, said indentations gradually increasing in depth in proportion to the increase in depth of the corrugations. 60
15. An expansion shield of sheet metal in the form of a cylinder having a bore of gradually decreasing cross sectional area, helical corrugations of constant pitch but increasing depth in the walls of the shield, and reinforcing indentations in the corrugations extending longitudinally of the shield, said indentations gradually increasing in depth in proportion to the increase in depth of the corrugations. 65
16. An expansion shield of sheet metal in the form of a cylinder having a bore of gradually decreasing cross sectional area, helical corrugations of constant pitch but increasing depth in the walls of the shield, and reinforcing indentations in the corrugations extending longitudinally of the shield, said indentations gradually increasing in width and depth and being of greatest width and depth on the corrugations of greatest depth. 70
17. An expansion shield of sheet metal in the form of a cylinder having a bore of gradually decreasing cross sectional area, helical corrugations of constant pitch but increasing depth in the walls of the shield, and reinforcing indentations impressed in the exterior corrugations of the shield. 75
18. An expansion shield of sheet metal in the form of a cylinder having a bore of gradually decreasing cross sectional area, helical corrugations of constant pitch but increasing depth in the walls of the shield, and parallelly extending indentations in the exterior corrugations of the shield. 80
19. An expansion shield of sheet metal in the form of a cylinder having a bore of gradually decreasing cross sectional area, helical corrugations of constant pitch but increasing depth in the walls of the shield, and means interrupting the normal increase in cross sectional dimension of the corrugations at points near the maximum depth of the same. 85
20. An expansion shield of sheet metal in the form of a cylinder having a bore of gradually decreasing cross sectional area, helical corrugations in the walls of the shield of constant pitch but increasing depth, and indentations in the shield extending across the helical corrugations, said indentations increasing in depth in proportion to the increase of the depth of the corrugations. 90
21. An expansion shield of sheet metal in the form of a cylinder having a bore of gradually decreasing cross sectional area, helical corrugations in the walls of the shield of constant pitch but increasing depth, and parallel indentations in the shield extending across the helical corrugations at points on either side of the major axis of the shield. 95
22. An expansion shield of sheet metal in the form of a cylinder having a bore of gradually decreasing cross sectional area, helical corrugations of constant pitch but increasing depth in the walls of the shield, the corrugations in the bore of the shield forming threads to cooperate with a lag screw, and longitudinally extending indentations in the corrugations on the outside of the shield gradually increasing in depth in proportion to the depth of the corrugations whereby certain portions of the interior threads are of constant depth longitudinally of the length of the shield. 100
23. An expansion shield of sheet metal in the form of a cylinder having a bore of gradually decreasing cross sectional area, helical corrugations of constant pitch but increasing depth in the walls of the shield, the corrugations in the bore of the shield forming threads to cooperate with a lag screw, and longitudinally extending indentations impressed across the corrugations whereby certain portions of the threads are of constant depth longitudinally of the length of the shield.

In witness whereof, I hereunto set my hand this 7th day of Jany, 1921.

JOHN EDWARD OGDEN.

Witness:

I. B. MOORE.
